UNITED STATES PATENT OFFICE.

ELMER W. LUNDELL, OF PITTSBURGH, PENNSYLVANIA, ASSIGNOR TO SEYLER MANUFACTURING COMPANY, OF PITTSBURGH, PENNSYLVANIA, A CORPORATION OF PENNSYLVANIA.

INSULATOR SUPPORTING BRACKET.

Application filed May 1, 1926. Serial No. 105,980.

This invention relates to improvements in insulator supporting brackets, and more particularly to insulator brackets of the secondary rack type of brackets or supporting structures.

In insulator supports of the character specified, the construction usually comprises a base, a plurality of insulator supporting arms secured to the base and projecting outwardly therefrom, a rod carried at the outer ends of the arms, a series of insulators of the spool type mounted on the rod between the arms, and a number of bolt holes formed in the back or base through which bolts may be passed for securing the structure to a wall, pole, or other means.

Supports of the type above described have proven unsatisfactory in several respects, for example, considerable trouble has been met with due to the construction of the base member and the means co-operating therewith for securing the insulator supporting arms thereto. Troubles have also been encountered on account of the weak cross sectional area adjacent the rivet openings and through which the rivets pass.

Among the objects of the present invention are, to provide a bracket structure of the type specified having a new and improved base portion; a base portion formed with improved means for rigidly securing the insulator supporting arms or units to the base and to prevent displacement thereof relatively to the base; to provide a construction having a metallic mass of considerable cross sectional area adjacent the rivet openings; a construction doing away with the separable spacing members; a base construction having supporting arm receiving means providing top, side, and bottom contacting or bearing surfaces for said arms; and to provide a construction comprising a receiving means for the inner ends of the supporting arms whereby said arms may be readily positioned therein in the operation of assembling the parts.

In the accompanying drawings, which illustrate an application of my invention;

Figure 1, is an elevational view of a bracket or secondary rank structure constructed in accordance with my invention.

Figure 2, a top plan view of the base portion of the bracket structure;

Figure 3, a part plan and a part sectional

view, the section being taken on line III—III 55 of Figure 1;

Figure 4, a part plan and a part sectional view, the section being taken on line IV—IV of Figure 1, and

Figure 5, a view similar to Figure 4, showing a modified form.

Referring to the drawings and as preferred, my improved insulator bracket or secondary rank construction comprises a base formed of two similar angle plate members 65 5, each having a base portion 6, and a vertically extending wall portion 7. The portions 6 of the said members are formed with the usual bolt receiving openings 8, designed to receive bolts, not shown, for securing the 70 rack structure to a wall or other support.

At spaced apart distances along the wall 7, of each member 5, the metal is pressed inwardly to form means entering into the formations of pockets for receiving the inner 75 ends of insulator supporting arms or units 9. This arm receiving portion, it will be noted, is shaped to provide a wall *a* having a top contacting edge for the arm 9, walls *b* having side contacting portions and a bottom contacting portion *c* for said arm, the latter being disposed between the side walls *b*. In the manufacture of the supporting bracket, the members 5 are formed or shaped separately, after which they are assembled in 85 the manner particularly shown by Figure 2.

It will be seen that when the two angle members constituting the base are assembled, the base structure will comprise two base portions and two parallel walls, said walls 90 having portions thereof in contact with each other and shaped to form pockets 10 for receiving the inner ends of the insulator supporting arms 9.

Arms 9 are preferably made from a single 95 piece of metal bent upon itself to form, an outer eye 9^a, inner end portions 9^b, adapted to straddle the contacting portions *a* of the parallel walls; and intermediate portions 9^c.

When the parts are assembled the inner 100 ends 9^b of the insulator supporting arms, are entered in the pockets 10, with portions of the respective ends in contact with the walls *a*, and flanges *e* of the said ends in contact with the upper edges of the walls *a*. The side and bottom portions of the said 105 arm ends engage with the side walls *b*, and the bottom portions *c*. This construction

provides bearings for the flanges *e* of the arms, as well as bearings for the front, sides, and bottoms of the ends of the insulator supporting arms.

- 5 12 designates rivets adapted to be passed through openings formed in the supporting arms and the base. Attention is called to the fact that in both forms of my invention, (see Figs. 4 and 5) the constructions 10 provide a relatively large metallic bearing for the rivets, or strong cross-sectional metallic portions adjacent the rivet openings.

The construction, including the said walls, contacting surfaces, the mass of metal adjacent the rivet openings, and the rivets passed through the said metal, provides simple and efficient co-operating means for rigidly securing the supporting arms to the base and preventing displacement of the 20 said arms when subjected to the strains and stresses met with in service.

In the form of Figure 5, I have shown a slight modification from the construction of the form of Figure 1. In this latter form 25 the angles between the walls *a'* and *b'* are not as abrupt as is the first form and the sides of the inner ends of the insulator supporting arms are shaped as shown at *h* to correspond with the contour of the walls *a'* 30 and *b'*; otherwise the construction is the same.

I have shown the usual rod 13 for carrying the insulator spools 14, this rod being inserted through the eyes 9^a of the arms 9.

35 What I claim is:

1. In an insulator supporting bracket, a base including parallel walls, said walls having contacting portions and shaped to form an arm receiving pocket adjacent the contacting portions, an insulator supporting arm having a portion thereof entered in the pocket and straddling the contacting base portions, and means co-acting with the con-

tacting portions for fixedly securing the arm in the pocket. 45

2. In an insulator supporting bracket, a base including parallel walls, said walls having contacting portions and shaped to form an arm receiving pocket adjacent the said portions, an insulator supporting arm having 50 its inner end straddling the contacting portions and located in the pocket, and means passed through the inner end of the arm and the said contacting portions for securing the arm in the pocket. 55

3. In an insulator supporting bracket, a base including two metallic angle members having longitudinally extending parallel walls, said walls at intervals along their lengths being brought into contact with each other and being spaced apart between the contacting portions, and an insulator supporting arm rigidly secured to the said contacting portions of the base. 60

4. In an insulator supporting bracket, a 65 base including two spaced metallic angle members having longitudinally extending parallel walls, said walls at intervals along their lengths being brought into contact with each other, and an insulator supporting arm 70 having its inner end straddling the contacting portions and riveted thereto.

5. In an insulator supporting bracket, a base including two spaced metallic angle members having longitudinally extending 75 parallel walls, said walls at intervals along their lengths being brought into contact with each other and shaped to receive insulator supporting arms, a metallic insulator supporting arm having divided inner ends 80 straddling the contacting portions thereby forming with the said contacting portions a mass of metal for a rivet, and a rivet passed through said metallic mass.

In testimony whereof I affix my signature.
ELMER W. LUNDELL.
